UNITED STATES PATENT OFFICE

147,623

DESIGN FOR A TOILET PAPER HOLDER

Myron K. Silvers, Seattle, Wash.

Application August 20, 1946, Serial No. 132,674

Term of patent 7 years

(Cl. D4—3)

To all whom it may concern:

Be it known that Myron K. Silvers, a citizen of the United States, residing at Seattle, Washington, has invented a new, original, and ornamental Design for a Toilet Paper Holder, of which the following is a specification, reference being had to the accompanying drawing, forming a part thereof, in which

I claim:

The ornamental design for a toilet paper holder, substantially as shown.

MYRON K. SILVERS.
